Design No. 17,792, dated October 18, 1887.

UNITED STATES PATENT OFFICE.

HENRIETTA F. DUKE, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 17,792, dated October 18, 1887.

Application filed August 8, 1887. Serial No. 246,466. Term of patent 3½ years.

To all whom it may concern:

Be it known that I, HENRIETTA F. DUKE, of the city, county, and State of New York, have invented and produced a new and original Design for a Pattern of a Lady's Costume; and I do hereby declare that the engraved prints accompanying this specification convey to any one accustomed to using paper patterns a clear understanding of how a garment made up by the pattern will appear.

The design shows a basque and a round walking skirt. The basque displays jacket-fronts with folded back lapels nearly to the waist-line and exhibits a full vest between them, a close-fitting back that displays under-folded plaits below the waist-line of the middle three seams, a standing collar crossing the vest, a standing collar that exhibits its ends lapped upon the vest-collar, a turn-over collar falling from its upper edge, and coat-sleeves. The lower outline of the vest describes a point at the center of the front, and that of the basque describes high short sides and a square postilion back. The skirt exhibits a deep front drapery of rounded outline descending quite near the edge at the center and much shorter at the sides, the drapery displaying draping plaits below the belt-line in numerous folds, a back drapery that exhibits plaits which flare in fan fashion at the leftside, where the drapery falls to the edge of the skirt, and then describes a rounding outline toward the right side, where it is lifted high.

What I claim as my invention, and desire to secure by Letters Patent, is—

The design for a lady's costume, as shown in the engraved print accompanying this specification.
